FURNACE

Filed Feb. 9, 1928

UNITED STATES PATENT OFFICE

JOHN SPOUSTA, OF RIVER ROUGE, MICHIGAN

FURNACE

Application filed February 9, 1928. Serial No. 253,147.

My invention relates to a new and useful improvement in a furnace adapted particularly for use for heating purposes and especially a furnace used for generating steam whether used for heating or power purposes, the present invention being an improvement on my invention set out in my application for Letters Patent Serial No. 167,409, filed February 11, 1927.

It is an object of the present invention, in addition to attaining the objects attained by the original invention, set out in the application referred to, to provide an upper section whereby the communication of the inner positioned sections with the outer sections may be effected at other points than directly opposite the outlet opening of the steam dome.

It is another object of the invention to provide a steam furnace of this class in which the steam may be led therefrom without an excess of moisture from the furnace with the steam.

Other objects will appear hereinafter.

The invention consists in the combination and arrangement of parts hereinafter described and claimed.

The invention will be best understood by a reference to the accompanying drawings, which form a part of this specification and in which,

Fig. 1 is a central vertical sectional view in fragment of a furnace embodying the invention.

Fig. 2 is a sectional view taken on line 2-2 of Fig. 1.

Fig. 3 is a fragmentary sectional view of the structure shown in Fig. 1 taken on the line indicated by the section line 3-3 of

Fig. 2.

The invention primarily relates to the inner positioned section directly beneath the steam dome and to illustrate the use of the invention I have shown in the drawings a furnace embodying a base 9, projecting up-

wardly from which is a supporting drum 10 having an opening 11 formed in the forward side thereof and closed by a suitable door 12, having a smaller door 13 hingedly mounted thereon, as a closure for the air vent opening 14. Projecting inwardly from the upper edge of this door 12 is a flange 15, on the upper surface of which is the bead 16, which engages in a groove 17 formed in the supporting section of the furnace positioned thereon. As shown in the drawing, this supporting section is formed from an outer wall 18 and an inner wall 19, spaced therefrom. Formed integral with the inner wall 19 and projecting inwardly thereof is a globe shaped container 20 which is provided with the upwardly projecting, interiorly threaded neck 21 in which is threaded a nipple or pipe section 22 which also threads into the neck 23 of the flat disc-like hollow section or member 24 serving to bind the section or member 24 on the container 20. An upwardly projecting neck 25 is formed on this section or member 24 and connected by the nipple or pipe section 26 to the downwardly projecting neck 23' on the disc-like tubular section or member positioned thereabove, the succeeding structure being but a duplication of these parts. Threaded into an opening 27 formed in the top 28 of the supporting section is a nipple or pipe section 29 which threads into an opening 30 formed in the base 31 of a section comprising the outer wall 32 and an inner wall 33 which is bulged inwardly to form the inwardly directed hollow, comparatively shallow container 34 and to form, with the disc-like sections, sinuous passages for the escape of gas. Threaded into the opening 35 formed in the upper wall 36 of this section is a nipple or pipe section 37 which serves to bind thereto the section positioned thereon, this section being a duplicate of the section below. The number of nipples or pipe sections 29 and 37 uti-

lized may be varied, although in the structure illustrated I prefer to use three.

The invention comprises in combination with the structure shown, the uppermost centrally positioned or disc-like section, this section forming the hollow container 38 having the downwardly directed neck 39 which is interiorly threaded for the reception of the nipple or threaded pipe section 40 which serves to bind this container 38 in communication with the centrally positioned or disc-like sections below. An upwardly projecting neck 41 is interiorly threaded for the reception of one end of the pipe section 42, the other end of which projects through the opening in the dome 43 and is retained in position therein by the jam nut 44 and the packing 45. Formed in the lower wall 46 of this container 38 are a plurality of openings 47. Threaded into these openings 47 are nipples or pipe sections 48, which serve to bind the lower wall 46 to the outer section positioned therebelow. A similar nipple or pipe section 49 is threaded into an opening formed in the top wall 50 and into an opening formed in the base of the dome 43. In the structure shown, I have provided three sets of these openings so that the container 38 comprises a central main body portion communicating through passages 51 with the space 52 and through the openings 49 with the lowermost section and the dome 43. It will be noted in Fig. 2 that the walls 53 and 54 which define the space or chamber 52, do not extend around the container 38 completely but terminate at the forward side of the boiler to provide a cleanout space 55 which is normally closed by the door 56.

By connecting the central positioned sections through the container 38 with the interior of the outer sections, the water level may be maintained at a point below the upper wall 50 of the container 38 and when this water is heated so that boiling or bubbling will take effect in the innermost sections, on account of the communication with the outer sections, a forcing of the water through the pipe section 42 will be prevented, thus assuring a drier steam than would be the case were the container 38 to be replaced with one of the lower positioned central sections.

The upper section or container 38 may, from the description given, be properly described as a section having a central circular portion surrounded by and communicating with a circular tubular ring portion, this ring portion communicating through openings with the outer sections.

While I have illustrated and described the preferred form of my invention, I do not wish to limit myself to the precise details of structure shown, but desire to avail myself of such variations and modifications

as come within the scope of the appended claims.

Having thus described my invention what I claim as new and desire to secure by Letters Patent is:

1. A furnace of the class described, comprising: a plurality of duplicate double walled sections, with the spaces between said walls in intercommunication, the inner wall of each of said sections being bulged inwardly away from the outer wall, a plurality of centrally disposed disc-like hollow intercommunicating members enclosed by said double walled sections, the edges of adjacent disc-like members extending in overlapping spaced relation to said bulged walls, the space between said bulged walls and said disc-like members forming sinuous passages for the escape of gas, a supporting section comprising spaced walls from continuations of the walls of the double walled sections, the space between said walls being in communication with the space between said double walled sections, a centrally disposed hollow globe shaped container connected to said supporting section and said disc-like members and establishing communication between the enclosed spaces of said sections and members and providing support for said disc-like members, a top disc-like section in intercommunication with said disc-like member, a ring partially embracing said top disc-like section and communicating therewith and resting upon and communicating with the uppermost of said double walled sections, a hollow top section communicating with said top disc-like section and with said double walled sections, and having an exit flue in communication with said sinuous passages said supporting section enclosing a combustion chamber space.

2. A furnace of the class described, comprising: a plurality of duplicate double walled sections, with the spaces between said walls in intercommunication, the inner wall of each of said sections being bulged inwardly away from the outer wall, a plurality of centrally disposed disc-like hollow intercommunicating members enclosed by said double walled sections, the edges of adjacent disc-like members extending in overlapping spaced relation to said bulged walls, the space between said bulged walls and said disc-like members forming sinuous passages for the escape of gas, a supporting section comprising spaced walls from continuations of the walls of the double walled sections, the space between said walls being in communication with the space between said double walled sections, a centrally disposed hollow globe shaped container connected to said supporting section and said disc-like members and establishing communication between the enclosed spaces of said sections and members and providing support

for said disc-like members, a top disc-like hollow section communicating at its central portion with said disc-like members and having a hollow portion overlying the uppermost of said double walled sections and communicating therewith, a hollow top section communicating with said top disc-like section and having an exit flue in communication with said sinuous passages.

5 10 In testimony whereof I have signed the foregoing specification.

JOHN SPOUSTA.
